MAGNETIC DRIVE CONSTRUCTION

George E. Ford, Brighton, N. Y., assignor to Qual-
itrol Corporation, East Rochester, N. Y., a cor-
poration of New York

Application February 24, 1947, Serial No. 730,646

6 Claims. (Cl. 172—284)

1

This invention relates to a magnetic drive. An object of the invention is the provision of a generally improved, less expensive, and more satisfactory magnetic drive, and the provision of an improved, less expensive, and more satisfactory method or process of manufacturing such a drive.

Magnetic drives are used in many different locations, for driving many different things. For many uses, the magnetic drives already known are quite satisfactory. However, particularly difficult conditions of use are involved when the magnetic drive is immersed in a body of fluid containing magnetic foreign matter, such as iron filings, steel chips, etc., and it is one of the objects of the present invention to provide a drive which is particularly satisfactory under those conditions of use.

Still another object is the provision of a drive which may be mounted to turn on a horizontal or approximately horizontal axis, which axis is located below the liquid level of the tank or container in which the magnetic drive is located, and yet which will have a long trouble-free life notwithstanding the fact that there may be metallic chips in the liquid in which the drive is immersed.

A further object is the provision of an improved construction for mounting the moving parts of the magnetic drive and for limiting the extent of movement thereof, which construction gives a more rigid and satisfactory bearing to the moving parts and which also is relatively inexpensive to make.

A still further object is the provision of a magnetic drive construction so designed that one of the main mounting members, which in prior magnetic drives has heretofore required extensive machining, requires very little machining in the present improved construction.

A still further object is the provision of simplified, improved, and less expensive methods of manufacturing a magnetic drive.

These and other desirable objects are accomplished by the construction disclosed as an illustrative embodiment of the invention in the following description and in the accompanying drawings forming a part hereof, in which:

Fig. 1 is a front elevation of a construction in accordance with a preferred embodiment of the invention;

Fig. 2 is a section taken substantially on the line 2—2 of Fig. 1, on an enlarged scale;

Fig. 3 is a section taken substantially on the line 3—3 of Fig. 2; and

Fig. 4 is an exploded view of a fragment of the

construction shown in Fig. 2, at an intermediate stage in the manufacturing operation.

The same reference numerals throughout the several views indicate the same parts.

5 There is indicated at 11 a wall of a tank or container, which may be a pressure container holding liquid under substantial pressure, but is not necessarily so, as the liquid in the container 11 may be at atmospheric pressure. 10 Merely as an illustrative example, the container 11 may be an electric transformer casing, filled with insulating oil. The container is provided with an opening 13 surrounded by a thickened flange 15 to which is secured, as by bolts 17, the main mounting plate or closure plate 19 which extends entirely across the opening 13 in an imperforate manner, thus completely closing and sealing the opening 13. If desired, a gasket 21 mounted in an annular groove on the rear face of the main plate 19 may press against the front of the flange 15 on the tank, thus aiding in sealing the joint between the plate 19 and the tank.

25 Heretofore a main closure plate or mounting plate such as the plate 19 has been so designed as to require a number of machining operations, usually on both its front face and its rear face. According to the present invention, this main plate 19 is designed as a forging, and requires practically no machining operations. The few machining operations which are required consist merely of the formation of the annular groove for receiving the gasket 21 (if such a gasket is desired, it being frequently omitted) and the machining (if necessary) of the periphery or circumference of the plate in order to fit the bezel as mentioned hereafter, and the drilling and threading of the radial holes in which the bezel holding screws fit, as mentioned hereafter, and the drilling of the marginal holes through which the holding bolts or screws 17 extend.

30 In order to reduce, to a great extent, the machining which would otherwise be required, the mounting plate of the present invention has its central portion of its rear face originally forged in the shape shown in the left hand part of Fig. 4 of the drawings, including an annular bevelled shoulder 27 surrounded by an upstanding flange 29. A metallic tube 31 has its forward end flared as at 33 at an angle to fit the bevelled shoulder 27. The parts are brought together from the 35 position shown in Fig. 4 so that the flare 33 fits against the angular shoulder 27, and then the upstanding flange 29 is staked down or bent over from the upstanding position shown in Fig. 4 to the position shown at 29a in Fig. 2, thus 40 overlying the flared portion 33 of the tube 31 and

holding the tube securely and immovably to the rear face of the main mounting plate 19.

The rotatable shaft of the magnetic drive is indicated at 41 and is supported by passing with a snug rotary fit through central holes in two cup shaped bearing members 43 and 45 which are pressed into and have a tight press fit in the tube 31, at points therein which are spaced from each other and also spaced from the front and rear ends of the tube. Near its forward end the shaft 41 carries a spacing member 47, in front of which is a permanent magnet 49 usually and preferably of approximately U-shape, fixed on the shaft by a staked or riveted portion 51. In front of the magnet 49 the shaft has a reduced portion projecting forwardly as at 53 and terminating in a somewhat pointed end 55 having a small flat extremity bearing against the flat central part of the rear face of the member 19.

The magnetic drive shaft 41 may be driven in various ways, depending upon what condition is to control the magnetic drive. If the drive is to be responsive, for example, to liquid level, there may be provided a float 61 mounted on a float arm 63 extending approximately radially with respect to the shaft 41, through a diametrical hole in a hub or cap member 65 having an axial bore, which receives and is mounted on the rear end of the shaft 41. A pin 67 pins the cap 65 to the shaft 41, and the outer end of the pin is sunk below the outer face of the cap 65, and the cap 65 is peened over the outer end of the pin 67 to hold it in place. The float rod 63 is held in place in its bore by means of a set screw 69 threaded into a radial opening in the cap 65.

It will be noted that the float arm swings approximately in a plane perpendicular to the axis of the shaft 41 and located between the rear end of the tube 31 and the rear bearing cup 45. The rear end of the tube 31, rearwardly of the cup 45, may be notched out or cut out along one side so as to leave a top edge 71 and bottom edge 73 which form stops or abutments for limiting the upward and downward swinging of the float arm 63, and this same notch extends axially along the tube 31 approximately to the rearmost bearing member 45, thus allowing ample space for access to the cap 65 when initially assembling the cap on the rear end of the shaft 41 and when assembling the float rod 63 in the cap and tightening the set screw 69, which operations are performed through the large notch with little trouble.

With this arrangement, a particularly satisfactory construction results. Machining work is reduced to a minimum. The assembly is easy and can be done inexpensively. The support of the shaft 41 is particularly rigid and effective, and the shaft is protected from lateral blows or damage by the sturdy tube 31 which, in turn, is mounted in an extremely sturdy yet easy manner on the rear face of the main plate 19. Forwardly of the rear cup bearing 45, the tube 31 has no lateral openings whatever, hence chips cannot readily get to the magnet 49. As the insulating oil or other liquid within the tank 11 circulates around the parts of the magnetic drive, any chips or other magnetic foreign matter carried thereby and coming within the magnetic influence of the magnet 49 will be stopped by the outside of the tube 31 and will simply cling to the outer surface of the tube, where they are far away from all moving parts and will do no damage. Any chips which happen to get inside the rear end of the tube 31, rearwardly of the cup bearing 45, are so far away from the magnet 49

that they are not subject to any substantial magnetic influence and so are not likely to be drawn toward the bearing joint between the shaft 41 and the cup 45. The magnetic influence being so slight at this rear bearing of the shaft 41, any chips located at that point are likely to be easily washed away by the continued circulation of the oil or other liquid within the tank 11. The large notch whose upper and lower edges are shown in 71 and 73, respectively, promotes free circulation of the oil or other liquid within the rear end of the tube 31 so as to allow sufficient circulation to wash away any chips that may be carried to this part of the apparatus.

15 The magnetic drive consists of two separate units, a driving unit and a driven unit. The driving unit comprises the parts already described, and the novelty of this present invention resides mainly in this driving unit. The driven unit, detachably mounted on the front of the main plate 19, may be of any suitable form, subject to the influence of the driving magnet 49. For example, in the form here shown, there is a bezel 81 having a rearwardly extending annular flange fitting snugly over the periphery of the main mounting plate 19 as seen in Fig. 2, and held thereto by screws 85 extending radially into tapped openings in the edges of the main plate 19. This bezel carries a case 83 having a stepped marginal edge, the outer step of which has a tight press fit in the bezel, and a U-shaped gasket 86 pressed tightly between the bezel and the front step of the case 83 embraces the edge of a closure glass 87 extending across the front of the case.

30 35 At the center of the case 83, in axial alignment with the shaft 41, is a stationary pivot 87 mounted by being riveted to the case. Rotatable on this pivot 87 is a sleeve 89 to which is fixed a pointer 91 and a permanent magnet 93, preferably of U-shaped form as seen, which constitutes the driven magnet and is under the magnetic influence of the driving magnet 49, so that whenever the magnet 49 turns on its rotary axis, the magnet 93 will follow. The pointer 91 sweeps across 40 suitable index markings or graduations 95 on a dial plate 97 secured to the case 83 by rivets 99.

45 The improved construction herein disclosed is particularly effective in eliminating trouble heretofore caused by the driving unit being immersed 50 in oil or other liquid containing magnetic foreign matter such as chips or filings, which have heretofore been carried around by the circulation of the oil or other liquid in the tank in such manner as to come into contact with the magnet of 55 the magnetic drive and gradually build up an accumulation of foreign matter on the magnet to such an extent that frequently the accumulation of foreign matter has contacted with other parts and thus prevented proper functioning of the 60 magnetic drive, and in many instances the foreign matter has gotten in the bearings of the magnetic drive shaft. These difficulties are avoided by the present construction, and the magnetic drive herein disclosed can be used efficiently in 65 a submerged position, as distinguished from many of the prior magnetic drives which are not suitable for use in a submerged position and which can be used effectively only when the magnet is located above the level of the liquid so as to be 70 away from any magnetic foreign matter carried by the liquid.

75 It will be understood, of course, that the main plate 19, and preferably also the tube 31, shaft 41, cups 43 and 45, and in fact all of the metallic parts other than the permanent magnets 49 and

83, are made of some non-magnetic metal or alloy, such as copper, brass, aluminum, etc.

In assembling the driving unit, the cups are preferably first pressed into their proper locations in the tube, then the shaft with the magnet already fixed thereon is inserted in the bearing holes of the cups, and then the flared end of the tube is assembled to the main plate and the flange on the plate is swaged or staked down onto the flare of the tube. The cap may be pinned to the rear end of the shaft either before or after the tube is fastened to the plate.

Certain subject matter disclosed but not claimed herein is claimed in the co-pending application of George E. Ford, Serial No. 632,683, filed December 4, 1945, now Patent No. 2,473,581, patented June 21, 1949, for indicating instruments.

It is seen from the foregoing disclosure that the above-mentioned objects of the invention are admirably fulfilled. It is to be understood that the foregoing disclosure is given by way of illustrative example only, rather than by way of limitation, and that without departing from the invention, the details may be varied within the scope of the appended claims.

In addition to the advantage of eliminating certain machining operations which have heretofore been required, the present construction has the further advantage that, by eliminating machining operations, the danger of uncovering porosity in the forging or casting is also eliminated. Hence, the main plate 19, whether it be a forging (as preferred) or a casting, has a hard, dense rear surface, so that an exceptionally tight and leak-proof construction is obtained.

What is claimed is:

1. A magnetic drive unit comprising a plate adapted to form a closure for an opening in a tank, said plate having an imperforate portion adapted to be mounted in position to extend across the tank opening, an inclined annular seat on the rear face of said plate, a tube extending rearwardly from the rear face of said plate and having a forward end flared to seat on said inclined portion of said plate, a plurality of partitions extending across said tube at spaced intervals therein and forming bearings, a shaft extending longitudinally in said tube and having bearings in said partitions, and a magnet fixed to said shaft near the forward end thereof closely adjacent the rear face of said plate, one of said partitions being spaced substantially rearwardly from said magnet, and the portion of said tube between said one of said partitions and said plate being imperforate so that chips of magnetic material surrounding said tube cannot come into contact with said magnet.

2. A magnetic drive unit comprising a plate adapted to extend across and form a closure for an opening in a liquid container or the like, a tube mounted on the rear face of said plate and extending rearwardly therefrom so as to extend through the opening into the liquid within the container when the plate is mounted across said opening, the rear end of said tube having a notch extending throughout only a portion of the circumference of the tube, a plurality of bearing members extending across the interior of said tube at spaced points therein, a shaft rotatably mounted in said bearing members, a magnet carried by said shaft and arranged in close proximity to the rear face of said plate, and a float arm operatively connected to said shaft near the rear end thereof and arranged in cooperative re-

lation to said notch so that the edges of said notch forms stops limiting the swinging movement of said float arm in both directions.

3. A magnetic drive unit including a mounting plate adapted to extend across and form a closure for a lateral opening in a liquid tank below the maximum liquid level therein, a tube extending rearwardly from the rear face of said plate and supported thereby, a plurality of cup shaped members each having a tight pressed fit inside said tube and arranged at spaced intervals therein, each of said cup shaped members having a hole therethrough, a shaft mounted for rotation in and extending snugly through and having bearings in said holes of said cup shaped members, at least one of said cup-shaped members being substantially imperforate except where said shaft passes through it and serving as a sealing partition to prevent foreign matter from passing axially along said tube past such partition, a magnet mounted on said shaft between said plate and that one of said cup shaped members which is closest to said plate, a float arm operatively connected to an end of said shaft remote from said plate, said float arm extending substantially radially with respect to said shaft, and abutment edges on said tube forming limit stops for engaging said float arm to limit the swinging thereof and thereby to limit the rotation of said shaft.

4. A magnetic drive unit comprising a plate having near the center of its rear face an annular seat, a tube having a front end flared outwardly and mounted against said seat of said plate, an integral flange on said plate overlying the flared end of said tube to hold said tube in place, a plurality of cup shaped members fitted within said tube at points spaced from each other and spaced from the front and rear ends of said tube, said cup shaped members having axial openings therethrough, a shaft extending through said axial openings and mounted for rotation therein, a magnet mounted on said shaft near the forward end thereof, between said plate and said cup shaped member closest to said plate, said magnet being in close proximity to the rear face of said plate and the portion of said tube between said cup shaped member and said plate being imperforate so that foreign matter may not enter laterally through said tube to said magnet, a float arm operatively connected to said shaft adjacent the rear end thereof, and marginal apertures extending through said plate in directions approximately parallel to said tube and at a substantial distance radially outwardly from said tube so that fastening means may extend through said apertures to fasten said plate to a liquid container or the like.

5. A magnetic drive unit comprising a plate having near the center of its rear face an annular seat, a tube having a front end flared outwardly and mounted against said seat on said plate, an integral flange on said plate overlying the flared end of said tube to hold said tube in place, a plurality of cup shaped members fitted within said tube at points spaced from each other and spaced from the front and rear ends of said tube, said cup shaped members having axial openings therethrough, a shaft extending through said axial openings and mounted for rotation therein, a magnet mounted on said shaft near the forward end thereof, between said plate and said cup shaped member closest to said plate, said magnet being in close proximity to the rear face of said plate and the portion of said tube between said cup shaped member and said plate

being imperforate so that foreign matter may not enter laterally through said tube to said magnet, a hub mounted on the rear end of said shaft, a pin connecting said hub non-rotatably to said shaft, said hub being peened over said pin, a substantially radial opening in said hub, a float arm mounted in said radial opening in said hub, said float arm extending approximately radially with respect to said shaft, and a float carried by said float arm.

6. A construction as described in claim 5, in which said float arm is mounted to swing approximately in a plane transverse to the axis of said shaft and located between the rear end of said tube and that one of said cup shaped members which is closest to the rear end of said tube, and in which a side wall of said tube between the rear end and said one of said cup shaped members is cut away to allow space for swinging movement of said float arm, the edges of said tube 20

adjacent the cut away portion serving as stops to limit the extent of swinging movement of the float arm and thereby limit the extent of rotation of said shaft.
